ATTORNEY

UNITED STATES PATENT OFFICE.

GUSTAV A. BEHRMANN, OF NEW YORK, N. Y.

SASH-HOLDER.

1,174,114.

Specification of Letters Patent. Patented Mar. 7, 1916.

Application filed January 5, 1916. Serial No. 70,348.

To all whom it may concern:

Be it known that I, GUSTAV A. BEHRMANN, a citizen of Germany, and a resident of New York city, in the county and State 5 of New York, have invented certain new and useful Improvements in Sash-Holders, of which the following is a specification.

This invention relates to a sash holder of novel construction, by means of which the 10 upper sash may be locked in a closed or more or less open position. The holder may be readily manipulated, prevents rattling, sustains the sash even with torn cords, and is inaccessible to house-breakers.

15 In the accompanying drawing: Figure 1 is a vertical longitudinal section of a sash holder embodying my invention; Fig. 2 a front view, and Fig. 3 a plan.

The device comprises essentially, a flanged 20 base plate 1, adapted to be fitted to the top rail 2 of the lower sash 3, to which it is attached by screws 4. Plate 1, carries a tubular casing 5, from the top of which, extend upwardly, a pair of rear lugs 6 constituting bearings. In these bearings is hung 25 by a pivot 7, an arched arm 8 having a tail piece 9 that extends across the open rear end of casing 5. This tail piece is engaged by one end of a coiled spring 10 which is 30 housed within the casing 5, and is affixed at its other end to the front wall thereof. Arm 8 is furnished at its free end with a concave 35 brake shoe 11 lined with a correspondingly shaped pad or cushion 12. This cushion is adapted to frictionally engage the central

bar 13 of the upper sash 14 against which it is firmly held by the spring 10. Owing to the action of this spring, the upper sash will be sustained from the lower sash at any elevation to which it has been set.

Through bearings 6 extends a transverse aperture 15, adapted to become alined with an aperture 16, formed in a collar 17 of arm 8. Through apertures 15, 16 may be projected, a pin 18, suspended from casing 5 by 40 a chain 19. When the upper sash is to be released, shoe 11 is withdrawn from bar 13 by manually swinging arm 8 forward, and pin 18 is passed through openings 15, 16 the 45 location of aperture 16 being such, that in 50 this position, the shoe is maintained out of contact with the upper sash as indicated by dotted lines in Fig. 1.

I claim:

A sash holder comprising a base plate 55 adapted to be secured to the top rail of a lower sash, a casing mounted on the plate and having a rear opening, bearings extending upwardly from the casing, an arched arm pivoted to the bearings and having a 60 tail piece that extends into the casing through the opening thereof, a spring within the casing that engages said tail piece, a concave brake shoe carried by the arm, and adapted to be projected into engagement 65 with a bar on the upper sash, and means for maintaining said shoe out of engagement with said bar.

GUSTAV A. BEHRMANN.
